Primary Examiner — Philip S Hyder*Assistant Examiner* — Ramzi S Almatrahi(74) *Attorney, Agent, or Firm* — Volpe and Koenig, P.C.(57) **CLAIM**

The ornamental design for a monitoring camera, as shown and described.

DESCRIPTION

FIG. 1 is a top, front and right side perspective view of a monitoring camera showing our new design;

FIG. 2 is a front elevational view thereof;

FIG. 3 is a right side elevational view thereof, the left side elevational view being a mirror image thereof;

FIG. 4 is a top, rear and left side perspective view thereof;

FIG. 5 is a rear elevational view thereof;

FIG. 6 is a bottom plan view thereof; and,

FIG. 7 is a top plan view thereof.

The broken lines depict portions of a monitoring camera in which the design is embodied that form no part of the claimed design.

The dot-dash lines denote the boundary of the claim and form no part of the claimed design.

1 Claim, 5 Drawing Sheets(56)
